CLAIM

The ornamental design for a large cabin overhead, as shown and described.

DESCRIPTION

FIG. 1 is a front perspective view of a large cabin overhead showing our new design;

FIG. 2 is a partial left front perspective view thereof;

FIG. 3 is another partial left front perspective view with the right side portion and outside wall removed;

FIG. 4 is a left perspective view thereof;

FIG. 5 is a left side view thereof;

FIG. 6 is a left rear perspective view thereof;

FIG. 7 is a right front perspective view thereof;

FIG. 8 is a partial right rear perspective view thereof; and,

FIG. 9 is a right side view thereof.

In FIGS. 1-9, broken lines indicate environmental structure that forms no part of the claimed design.

1 Claim, 9 Drawing Sheets
